(74) *Attorney, Agent, or Firm*—Osler, Hoskin & Harcourt LLP

(57) **CLAIM**

The ornamental design for a snowmobile headlight glass, as shown and described.

DESCRIPTION

FIG. 1 is a left side elevation view showing a snowmobile headlight glass according to our design;

FIG. 2 is a right side elevation view thereof;

FIG. 3 is a front elevation view thereof;

FIG. 4 is a top plan view thereof;

FIG. 5 is a bottom plan view thereof;

FIG. 6 is a front elevation view showing a typical snowmobile (in broken lines) including a snowmobile headlight glass according to our design; and,

FIG. 7 is a left side elevation view showing a typical snowmobile (in broken lines) including a snowmobile headlight glass according to our design.

Throughout the Figures, broken lines showing structure are for illustrative purposes only and form no part of the claimed design. Portions of the snowmobile headlight glass not shown in the Figures form no part of the claimed design.
